UNITED STATES PATENT OFFICE.

LEWIS J. BAZZONI, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SOLES.

Application filed November 18, 1918. Serial No. 262,955.

To all whom it may concern:

Be it known that I, LEWIS J. BAZZONI, a citizen of the United States, residing at Swampscott, in the county of Essex and 5 State of Massachusetts, have invented certain new and useful Improvements in Machines for Operating upon Soles; and I do hereby declare the following to be a full, clear, and exact description of the invention, such as will enable others skilled in the 10 art to which it appertains to make and use the same.

The present invention relates to machines for operating upon shoe soles prior to their 15 incorporation in a boot or shoe.

It is desirable from the standpoint of efficiency that machines which perform certain predetermined and definite operations upon shoe soles shall be so constructed that they 20 may perform the desired cycle of operations on a large number of soles successively without the constant attention of an operator.

Accordingly, one object of the present invention is to provide improved mechanism 25 for automatically guiding and feeding successive soles to the operating instrumentalities of the machine and for disposing of the soles at the completion of the operation.

To this end I have provided in combination with a sole treating machine, a sole magazine and a support for the soles when ejected from the magazine with feeler means cooperating with some characteristic contour of the sole for locating it on the support in proper relation to the operating means to insure successful treatment.

A further object of the invention is to provide mechanism which insures the proper guidance to the operating instrumentalities of successive soles which may vary 40 both in size and shape.

With these and other objects in view, the several features of the invention consist in certain novel features of construction, combinations and arrangements of parts herein-after described and claimed the advantages of which will be obvious to those skilled in the art from the following description:

The preferred embodiment of the invention is illustrated in the accompanying drawings in which Figure 1 is a side elevation of a sole molding machine having the present invention incorporated therein; Fig. 2 is a front elevation of the right side of

the twin machine shown in Fig. 1; Fig. 3 55 is a plan view of the magazine and a part of the table shown in Fig. 1; Fig. 4 is a plan view of the table similar to Fig. 3 but taken on a section line passing below the magazine; Fig. 5 is a continuation of Fig. 60 4 showing the end of the table adjacent the molds and the lower mold; Fig. 6 is a section on the line 6—6 of Fig. 5; Fig. 7 is a section on the line 7—7 of Fig. 3; Fig. 8 65 is a longitudinal section through the table showing a part of the magazine and the transferring mechanism in its inoperative position; Figs. 9, 10 and 11 are vertical longitudinal sections through the table, similar to Fig. 8, showing the transferring mechanism in successive stages of its operation in transferring the sole to the molds; Fig. 12 70 is a detail view on an enlarged scale, showing the toe engaging sole positioning device; Fig. 13 is a perspective detail showing the actuating means for certain of the sole positioning devices; Figs. 14, 15 and 16 are detail views, on an enlarged scale, of the stop mechanism by which the machine is brought 75 to rest when the soles in both the magazines have become exhausted; and Fig. 17 is a view showing the mechanism for actuating the sole feeding mechanism.

The present invention is embodied in a sole molding machine which is provided 80 with two sets of cooperating molds adapted to work alternately. In the simplest and most efficient form of the invention which has yet been devised a sole magazine is provided for each side of the machine, and 85 guiding and feeding mechanism serves to transfer the soles successively from each magazine to an operative position between the molds. During this transferring movement the bottom sole of the stack is initially 90 dropped upon a table, the sole is then located and clamped in position, after which it is transferred bodily to a position between the molds. At the completion of the molding 95 operation the finished sole is discharged into a suitable receptacle and a new sole placed in position. This cycle of operations continues on each side of the machine until the stacks in both magazines are completely exhausted, after which the machine automatically 100 stops.

In the machine shown in the illustrated embodiment of the invention the right hand

magazine only is indicated in the drawings. The stack of soles S rest on a plate 20 which is supported above the table by legs 21 and 22. The toe ends of the soles are loosely engaged by a retaining member 23 which is rigidly connected to the plate 20 by a casting 24. The heel end of the stack of soles is positioned by an angular retaining member 25 extending upwardly from a bracket 26. In order that the magazine may be adjusted to accommodate different sizes of soles, the bracket 26 is arranged to slide toward and from the retaining member 23 and is secured in adjusted position by bolts 27 passing through slots 28 in the plate 20.

The lowermost sole in the stack is ejected from the magazine and dropped upon the table by a finger 32 (see Figs. 7 and 8) which reciprocates longitudinally through a slot 33 formed in the plate 20. (See Fig. 3.) As shown in Fig. 8, the finger 32 is pivotally mounted on a block 34 and pressed yieldingly upward by a leaf spring 35. A stop 36 is provided to limit this upward movement. The end of the finger projects above the plate 20 a sufficient height to engage the lowermost sole, and when the finger is moved to the right the sole is pushed through an opening 37 and dropped upon the table, as indicated at S'. When the finger is moved to the left, it is depressed by the lowermost sole and again lifted by the leaf spring when the finger is moved beyond the heel end. The block 34, which carries the sole ejecting finger, is secured to an endless belt 40 which passes around two loosely mounted pulleys 41 and 42 beneath the magazine at opposite ends. The belt is moved alternately in opposite directions by a dog 43 mounted in the upper end of a post 44, which has a reciprocating movement as will be hereinafter explained. The dog 43 has a pair of short fingers 45 which, when the dog is moved to the right, engage the ends of a bar 47 (see Fig. 7) secured to the belt 40. This causes the ejecting finger 32 to travel in the opposite direction toward the heel end of the sole where it can feed the sole onto the table when moved in the opposite direction. As the dog 43 has a greater path of travel than it is desired to impart to the ejecting finger the fingers 45 are short enough to clear the bar when the latter reaches the pulley 41 and starts to rise as it passes around the pulley. Thus the dog is free to continue its movement to the right, and on its return stroke the bar, which has been left in elevated position, is engaged by longer fingers 48.—Fig. 11, which move the belt in a direction to cause the ejecting finger 32 to deliver another sole to the table.

The sole after having been dropped upon the table is next definitely positioned so that when it is gripped by the transferring

mechanism and moved into operative relation with the molds the break imparted by the molding operation will be properly located. It has been determined that the break in the majority of soles is located approximately at the center of the sole measured along the medium line and, therefore, if this longitudinal center of the sole is brought to a fixed position relative to the molds the break will be formed in the desired place. Accordingly, means is provided for bringing the longitudinal center of the sole to a definite position with relation to the corresponding longitudinal center of the molds after the sole has been delivered to the table, and before it is engaged by the transferring mechanism. In order that the break may have the proper angular relation to the length of the sole means are also provided for determining the angular position of the sole before it is engaged by the transferring mechanism. It will be apparent that variation in the length of the sole will not affect its proper positioning with relation to the molds as the location of the sole is determined by its longitudinal center independently of the length.

The table upon which the sole is delivered from the magazine consists of two pairs of plates 51 and 52. The plates of each pair are separated, as shown in Figs. 3, 4, and 7, so as to permit the passage therebetween of certain parts of the transferring mechanism which are carried by a slide 53 arranged to travel in ways of which these plates form the gibs. The last part of the movement of the slide away from the molds is employed to open a pair of sole positioning arms which engage the sole in some characteristic part of its contour, as for example, the shank and determine its lateral position. As this movement is also employed to deliver the sole from the magazine, as has been described, it is apparent that the sole positioning arms must be subsequently released on the last end of the movement, after the sole has been delivered.

The sole positioning arms comprise members 54 mounted on vertical pivots 55 carried on the end of arms 56 projecting from the casting 24. The members 54 are interconnected by intermeshing gear segments 57 and the arms are normally moved toward one another by a spring 58 so that they act to center that portion of the sole engaged between them. The sole engaging portions of the arms are pivotally connected with the members 54 in order that the sole engaging extremities may be capable of a vertical movement made necessary by the particular construction employed which will be herein-after described. Referring to Figs. 3 and 7, the inner side of the sole is engaged by the arm 59 which is pivotally connected with a member 54 by a screw 60. The out-

side of the sole is engaged by the arm 61 pivotally connected with the other member 54 and provided with an adjustable sole engaging slide 62. The slide 62 may be secured in adjusted position on the arm by means of a nut so that the position of the sole may be varied to the right or left, as shown in Fig. 7, by a suitable adjustment of the slide 62. Variations in the shape of the characteristic sole contour used for the adjustment of the sole may thus be accommodated.

In order to open the arms against the action of the spring 58, one of the members 54 has an extension 63, Fig. 7, which engages a finger projecting from a slide bar 64. The slide bar is moved to the left (Figs. 3 and 4) to open the arms into sole receiving position by a latch 65 loosely pivoted on the left end of the bar 64. When the slide 53 is moving to the left into the position shown in Fig. 4, the end of the latch 65 is engaged by a beveled portion 66 on the end of the slide, and the bar 64 is thereby moved to the left and the arms are opened. After the bar has been moved a distance sufficient to open the arms to the desired extent, the bar is locked in this position during the delivery of the sole. The means for locking the bar comprises a detent 70 (Figs. 1 and 3) which is pressed by a spring 71 against the lower side of the slide bar 64. The lower side of the bar is provided with a notch 72 which receives the end of the detent 70, and is thereby held in retracted position. As soon as the detent has entered the notch, the latch 65 is lifted from engagement with the slide 53 by the engagement of an arm 73, integral with the latch 65, with a fixed lug 74. Thus, as soon as the bar 64 is under the control of the detent, its actuating latch is rendered inoperative.

The continued movement of the slide 53 to the left releases the detent so that the arms may close upon the sole as soon as it has been delivered to the table. The detent 70 is released by the engagement of a tail 75^a with the beveled portion 66 of the slide 50. This release occurs just as the slide 53 reaches its extreme position away from the molds. As shown in Figs. 3 and 7, the slide 53 has just reached its extreme position and the arms have closed under the action of the spring 58 to position the shank of the sole laterally.

The first part of the inward movement of the transferring slide 53 acts to swing the sole laterally about that part of the shank engaged by the positioning arms so as to correct the lateral position of the sole on the table, and also to move the sole in the line of its length to bring the longitudinal center of the sole into a predetermined relation with the molds. The lateral swinging of the sole is accomplished by a V shaped

heel engaging member which brings the end of the heel seat to a predetermined lateral position. The heel centering device is clearly shown in Figs. 4 and 8. The slide 53 is provided with an overhanging arm 75⁷⁰ upon which are pivotally mounted two wings 76 which are constrained to move in unison by segmental gear teeth 78. The wings are normally held toward one another by a spring 79 which is compressed between two fingers, one extending from each of the wings. The normal position of the wings is adjustable by means of a thumb nut 80 threaded onto a stud 81 which passes through a clearance hole in the finger adjacent the nut and is pivotally connected with the other finger. The thumb nut 80 is so adjusted that the wings will engage the sides of the rounded heel seat and bring it to a central position therebetween after which, if the sole is held from moving with the advancing wings, the spring 79 will yield, and allow the wings to advance slightly without affecting the position of the sole. After the shank of the sole is laterally positioned, as shown in Fig. 3, it will be apparent that the action of the heel centering device will cause the toe to swing to the right or left, thereby giving the sole a definite angular position with relation to the machine.

The longitudinal center of the sole is brought to a predetermined position by the movement of the slide 53 which travels in ways formed in two castings 85 and 86¹⁰⁰ (Figs. 1 and 2) which are supported in a horizontal position in front of the machine frame by brackets 87 and 88. The castings 85 and 86 are provided with a second pair of ways for a slide 89. The slides 53 and 89¹⁰⁵ may be conveniently distinguished as the upper or transferring and the lower slides respectively. The slide 89 is given a constant reciprocating movement toward and from the molds. The upper slide 53, however, which is actuated by the lower slide 89 has a variable reciprocating movement which varies in accordance with the size of the sole being delivered to the molds. The initial movement of the upper slide 53, during which the positioning of the sole occurs, is transmitted from the lower slide 89 through the following connections; referring to Fig. 8, the upper slide 53 has a pair of upwardly extending ears 90 between which is pivotally mounted a tree-armed bell crank. One arm 91 of the bell crank forms the movable jaw of a gripper which engages the sole at the proper time and carries it to the molds. The second arm 92 is provided with a seat for a spring 93, the other end of which bears against the slide 53, for the purpose of causing the arm 91 to grip the sole when the bell crank is free to turn. As shown in Fig. 8, the spring 93 is held under compression,¹¹⁰

with the gripper arm 91 elevated, by a latch 94 pivotally mounted on the slide 53. The arm 92 is forked to provide a downwardly extending finger 95 which passes through a hole in the slide 53. The finger 95 terminates in a rounded end which is engaged by a lug 96 projecting from the lower slide 89. As the three-armed bell crank is held in rigid position by the latch 94 the finger 95 may be considered as being an integral part of the slide 53. It is apparent that movement of the slide 89 to the right will transmit a corresponding movement to the slide 53 so long as the latch 94 holds the finger 95 down in the path of the lug 96.

The sole is positioned longitudinally by two movable abutments which engage respectively the toe and heel ends of the sole. The heel end of the sole is engaged by the wings 76 on the slide 53 and the toe is engaged by a finger 101 which is arranged to move simultaneously with the slide 53 but in the opposite direction. It is evident that these two abutments, one engaging each end of the sole and moving toward one another at the same speed, will position any size sole placed therebetween with its longitudinal center in the same place. After these two abutments have moved together so that they both engage the sole, the resistance offered to further movement is utilized to perform several operations as will be hereinafter apparent.

In order that the wings 76 and the toe engaging finger 101 shall be moved towards each other at equal speeds, the finger 101 is arranged to be moved by the initial movement of the lower slide 89 which pushes the upper slide and the wings 76 mounted thereon. One of the gibbs which retain the lower slide in its ways is in the form of a double raceway 102 (Figs. 7, 8 and 12). The finger 101 is pivotally mounted on an arm depending from a rack 103 mounted to slide in the upper part of the raceway. The rack 103 is connected with another rack 104 in the lower part of the raceway by a gear 105 which moves the rack 103 in a direction opposite to the rack 104 and at the same speed. The rack 104 is moved with the upper slide 53 by the finger 95 which is provided with a shoulder 107 to engage a block 106 projecting from the rack (see Fig. 13). The inoperative position of the toe engaging finger 101 is shown in Fig. 8 in which it has been swung down clockwise by a spring 108 surrounding the pivot of the finger and engaging an arm 109 formed integral therewith. As the lower slide 89 starts to move the upper slide towards the sole, the rack 103 is moved in the opposite direction which causes the arm 109 to engage the bottom of the raceway in which the rack 104 runs, and to be turned up into a vertical position as shown in Figs.

9 and 12. The wings 76 and the finger 101 thus draw together one or the other of them moving the sole between the members 59 and 62 in accordance with the position in which it happens to be found, until the sole is gripped between the wings and finger as shown in Fig. 9. In order that the sole shall not buckle at the center under this endwise pressure the arm 59 and the slide 62 are each provided with projections 110 which extend over the sole and hold it down on the table.

The pressure exerted on the sole between the abutments at the toe and heel is employed to cause the sole to be gripped by the transferring mechanism and to remove the finger 101 from the path of the sole so that the latter may be moved over the table to the molds. The wings 76 are capable of a slight yielding movement, as has been explained, when any substantial pressure is exerted on them by the sole. Pivotally connected on the table 53 between the wings 76 is a trip finger 111. This trip finger 111 is in such position that it will not be engaged by the sole until the wings 76 have been spread. Upon sufficient pressure being exerted on the wings to spread them, the heel end of the sole strikes the trip finger 111 and swings it about its pivot. The lower end of the trip finger is connected by a rod 112 with the depending end of the latch 94 so that a movement of the trip finger counter clockwise causes the latch 94 to be withdrawn from over the arm 92 and allows the three-armed bell crank to turn about its pivot and clamp the heel seat between the gripping arm 91 and a boss 113 on the end of the slide 53. A spring 114 normally holds the operative end of the trip finger 111 in detecting position. The movement of the three-armed bell crank in clamping the sole has caused the finger 95, which is integral therewith, to be lifted above the path of movement of the lug 96 which has been moving the upper slide. This causes the upper slide to stop as soon as the work has been gripped. The elevation of the finger 95 also lifts the shoulder 107 above the projection 106 by which the rack 104 is moved. As soon as the rack 104 is free from the action of the finger 95 the rack is returned to its original position as shown in Fig. 8, by a cable 115, one end of which is attached to the rack, and which passes over an idle pulley 116 to a counter weight 117 (Fig. 1). This permits the toe engaging finger 101 to move to the right or toward the molds and to swing downward below the table out of the path of the sole as it moves to the molds.

It will now be seen that any size sole will be positioned on the table with its longitudinal center in a predetermined relation to the molds. The transferring slide 53 has

5 moved up into proper position to clamp the heel end of the sole, which position will vary in accordance with the length of the sole. Since it is necessary to move the sole a certain distance to the molds, it is evident that the transferring slide must move the same distance but start and stop its transferring movement at variable points depending upon the length of the sole. As the longitudinal 10 center of the sole is always at the same place on the table the variation in position of the transferring slide at the time it grips the sole will be one half of the variation in the length of the soles and the movement after 15 gripping the sole will be constant. The lower slide 89 which imparts the transferring movement to the upper slide has a uniform travel as has been stated. The relation between the upper and lower slides, at the 20 time the upper slide starts its transferring movement, is determined by the length of the sole positioned between the wings 76 and the finger 101. The upper or transferring slide has been moved towards the molds by 25 a direct engagement with the lower slide until such time as the upper slide grips the work, at which time the direct connection between the upper and lower slides is broken. This initial movement of the upper 30 slide and the relative lost motion between the slides after the breaking of the connection vary in accordance with the length of the sole and means is provided for measuring this movement. The initial movement of 35 the upper slide determines the relation between the two slides when the lower slide again actuates the upper slide to transfer the sole to the molds.

40 The initial movement of the upper or transferring slide is measured by a measuring bar which forms an abutment for imparting the transferring movement to the upper slide.

45 Referring to Fig. 8 it will be seen that the sole gripping bell crank is provided with a third arm 120 which depends through the slide 53 and on its lower end carries a loosely and slidably mounted measuring bar 121. The right end of the measuring bar is provided with a lug 122 which is engaged by an abutment formed on the end of a lever 123 pivotally mounted on a stud 124 secured in fixed position on a part of the gib 125 of the lower slide. A spring on one end of the lever holds it normally in the position shown 55 in Fig. 8, such position being determined by a stop pin 126. When the slide 53 starts its initial movement to the right, the bar 121 is prevented from moving therewith by the engagement of the lug 122 with its abutment. As soon, however, as the slide has moved a sufficient distance to cause the sole gripping bell crank to turn about its pivot 60 to grip the sole, the measuring bar 121 is freed from engagement with the abutment. 65

Fig. 9 shows the measuring bar having been held stationary while the transferring slide was moving into sole gripping position. The movement of the bell crank in gripping the sole causes the measuring bar 121 to be tipped up at an angle, as shown in Fig. 10, at which time the lug 122 is below the abutment on the lever 123.

70 A locking device is provided to lock the measuring bar 121 in the position with relation to the transferring slide in which it is located when the sole is clamped, and this enables the measuring bar to be employed as an abutment to move the upper slide in the transferring operation. The locking device comprises a lever 127 pivotally mounted in the lower part of the arm 120. The pivoted end of the lever carries an eccentric roll 128 which at times grips the measuring bar 121 so as to prevent any relative movement 75 between the bar and the arm 120. As shown in Figs. 8 and 9, the lever 127 is in its unlocked position, it being held in this position by the engagement of the end of the lever with the slide 53. A tail on the lever 127 is connected with the slide 53 by a spring 129, so that when the measuring bar 121 is tilted by the gripping movement of the bell crank, the lever 127 is turned by the spring 129 until the eccentric roll 128 clamps the 80 measuring bar and prevents any relative movement between it and the arm 120.

85 The lower slide 89 is provided with an adjustable stop screw 130 which imparts movement to the transferring slide 53, picking it up at the end of the lost motion occurring after its movement has been interrupted as a result of gripping the sole. The screw 130 is adapted to engage the end of the measuring bar 121 and complete the 90 movement of the transferring slide to the mold by this means. The lower slide will always pick up the transferring slide, by means of the screw 130 and the bar 121, at the same point after which the two slides 95 will always move together the same distance to the molds. The lower slide always comes to a definite position adjacent the molds but as the relation between the slides is variable, as has been described, the position of the 100 transferring slide with relation to the molds is determined by the length of the sole being transferred. During the transferring movement of the upper slide the sole is pulled out from between the fingers 59 and 62.

105 The transferring slide 53 is moved by the lower slide 89, in the relative position shown in Fig. 10, to the position adjacent the molds shown in Fig. 11. This inward position is determined by the extreme inward position of the slide 89, which is always the same except that it may be adjusted for the purposes hereinafter set forth. In order that the sole may be firmly retained in its position relative to the molds 110

during the molding operation, provision is made for lifting the transferring slide at the same time that the sole would be lifted by the rise of the lower mold. The 5 castings 85 and 86 which provide ways for both the upper and lower slides are cut away adjacent the molds to receive two blocks 134 and 135 (see Figs. 5, 6, 7 and 11), in which are formed continuations of the 10 ways for the transferring slide. Each of the blocks 134 and 135 is provided with a depending slide 136, and the two slides are rigidly connected by a yoke 137. The slides 136 are each mounted in vertical ways 138 15 formed on the castings 85 and 86. The blocks 134 and 135 together with the transferring slide and plates 52 are lifted with the lower mold 139 by a pair of arms 140 extending from the mold block 141. The 20 mold block 141 which has a horizontal upper face is mounted to slide on an inclined surface formed on the lower mold carrier 142 so that by manipulation of a hand-wheel 143 a screw 144 may be turned to 25 adjust the mold up or down for the purpose of securing the proper pressure on the sole and adjustment to the thickness thereof. The arms 140 being carried by the mold block remain in fixed relation to the sole-engaging surface of the lower mold irrespective of any adjustment of the mold block to secure variation in pressure. It is apparent that the transferring slide will 30 always retain its relation with the upper surface of the lower mold, because the slide will be lifted more or less in accordance with the adjustment of the mold block 141 to secure varying pressures. The lifted position of the transferring slide is shown 35 in Fig. 11. By this construction, the sole gripping device carried by the transferring slide retains its grip upon the heel-seat during the molding operation. As shown in Fig. 3, the sole positioning arms 59 and 61 40 extend over the plates 52 which form that portion of the table which rises with the transferring slide. In order that these arms may rise with the transferring slide they are pivoted, as hereinbefore described. 45 As the lower mold descends, the transferring slide is dropped to its original level and returned to the magazine by the movement of the lower slide 89. The return movement of the transferring slide is produced by the engagement of a hook 145 secured to the under side of the slide with the lug 146 in which the stop screw 130 is mounted on the slide 89. When the hook is engaged by the lug 146, the parts are returned to their original position beneath the magazine, as shown in Fig. 8. 50 During return movement of the slides, the sole-gripping arm 91 releases its hold on the sole and an ejector throws the molded sole to one side of the machine. The grip- 55 ping arm 91 is opened to free the molded sole by a trip finger 147 (Figs. 8 and 9), which is loosely mounted on the end of a bracket 148. As the transferring slide approaches the trip finger, the end of the 60 finger engages a cam surface 149 formed on the arm 92 and as the trip finger is stopped from swinging to the left, the cam surface acts to depress the arm 92, thereby lifting the sole gripping arm 91 in which 65 position it is held by the latch 94 and freeing the sole. The movement of the sole gripping arm also causes the measuring bar 121 to be returned to horizontal position and the bar to be unlocked. As the 70 transferring slide continues its movement to the left, the lug 122 engages a finger 150 projected from the lever 123, which prevents further movement of the bar to the left, thus causing it to slide through its 75 bearing on the arm 120 and to be returned to the position shown in Fig. 8. 80 The means for ejecting the molded sole may be conveniently combined with the sole positioning arm 61. This arm, together 85 with the corresponding arm 59, is moved outwardly just prior to the arrival of the transferring slide in its extreme position to the left, and, in order that this opening movement may eject a sole from the machine, the arm 61 is provided with an extension 151 (Figs. 3 and 7) on which is pivotally mounted a depending finger 152. This finger just clears the plate 52 and is 90 restrained from a counter-clockwise movement by a lug 153. Thus, when the arm 61 and extension 151 are swung for the purpose of receiving a new sole, the finger 152 strikes the side of the molded sole and 95 throws it from the machine. On the return movement of the arm, after another sole has been delivered to the table, the finger is free to swing and pass over the sole into the position shown in Fig. 7. 100 In order that the positioning arms 59 and 61 shall not interfere with parts of the transferring table during its movement, means is provided for opening the arms slightly at the proper time to permit the 105 passage therebetween of such parts as might interfere with the sole engaging parts of the arms. The arms are opened by the action of a cam surface 156 formed on the transferring slide 53. This cam surface acts on the lower end 157 of a lever (see Figs. 3, 4, 7 and 8) pivoted at 158, the upper end 110 115 120 125 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

in the cam surface 156 causes the plunger to actuate the gear segment, thereby spreading the sole engaging arms. The end of the plunger is provided with a screw 163 by 5 which the spreading movement may be slightly adjusted.

The lower mold on each side of the machine is actuated to compress the sole by a toggle comprising links 166 and 167, (Figs. 10 1 and 17). The connection between the two links is acted upon by a crank-arm 168 which is actuated by a crank on the shaft 169 to alternately straighten and bend the toggle, as is usual in sole molding machines 15 of this type. In order that the sole may be placed between the molds before there is any chance of the molds having closed 20 too far to allow the proper positioning, the sole transferring movement is completed 25 during the first half of the upward movement of the lower mold.

The lower slide 89 is actuated to position and transfer the sole to the molds by the combined movement of the links 166 and 25 167 of the toggle. The upper link carries, pivotally mounted thereon, an arm 170 having a cam slot 171 which is engaged by a roll 172 on the end of an arm 173 integral with the lower link 167. The passage of 30 the roll 172 through the generally vertical portion of the cam slot 171 causes the cam arm to swing to the left, after which there will be no swinging movement imparted to the cam arm by the longer portion of the 35 cam path, since this part of the path is substantially perpendicular to a radius drawn therefrom to the center of swing of the link 167. The cam arm 170 is provided with a second slot 175 which receives a roll 174, mounted on one arm of a bell-crank lever 40 176. This lever is pivoted on a tie rod 177 which connects the brackets 87 and 88. The other arm of the bell-crank is connected, by block and slot, with the end of a bell-crank 45 178 loosely journaled on a second tie rod 179. The other arm of the bell-crank 178 carries the pivot 180 of another bell-crank 181. One arm of this bell-crank is connected by a link 182 with the ears 183 depending from the lower slide 89.

If the bell-crank 181 were rigidly mounted on the arm of the bell-crank 178, it is apparent that an invariable reciprocation would be imparted to the slide 89. It is 55 desirable, however, that the position of the slide 89 adjacent the molds shall be capable of slight adjustment. The desirability of this adjustment will be apparent from an inspection of Fig. 11, in which a sole is indicated in broken lines at 185, having a sharp break at the ball line and for use in a woman's high-heel shoe. It will be apparent that some of the distance between the end of the heel and the break has been 60 taken up by the sharp rise in the shank, 65

and that the transferring slide should be moved nearer to the molds in order to secure the correct position of the break. In order that this adjustment of the slide 89 toward the molds may be obtained without 70 disturbing the left position, or, in other words, that the travel of the slide 89 may be capable of slight adjustment, its starting point remaining the same in all cases, the shorter arm of the bell-crank 181 is provided with a roll 186 which slides within a straight raceway 187. The raceway 187 is pivotally mounted at 188 on the bracket 87 and rigidly connected with an arm 189, by which the angular position of the raceway 80 may be varied. The arm 189 is locked in adjusted position by hand nut 190. When the slide 89 is at the magazine end of the table or at the left in Fig. 1, the roll 186 coincides with the pivot 188 of the raceway 85 187, so that the raceway may be adjusted angularly without affecting the position of the slide. The angular position of the raceway 187 is so adjusted that as the roll 186 moves downwardly, the bell-crank 181 will 90 be turned about its pivot 180, thus increasing or decreasing the travel of the slide toward the mold. Fig. 17 shows the mechanical movement just described in such position that the lower mold has risen one-half of its full travel and the slide 89 has 95 completed its movement towards the molds.

A stop-mechanism is provided in the present invention which brings the machine to rest after the soles have been exhausted from both magazines. In order that the machine may not be stopped until the last sole in the magazines has been molded and ejected from the machine, the stop-mechanism is arranged to throw out the driving 100 clutch on the first idle stroke after the exhaustion of the soles. Each magazine is provided with a feeler which preferably operates through electrical connections to perform a preliminary step in the stopping 105 movement when the soles have become exhausted from the first magazine and to perform the second step when the soles have become exhausted from the other magazine. The second step puts the stop-mechanism in 110 operative condition, so that it is acted upon by a moving part of the machine during the first idle movement thereafter and the machine brought to a stop.

The feeler mechanism with which each 115 magazine is provided is illustrated in Figs. 7, 8 and 14. The bracket 24 carries an insulating plate 194 which provides a bearing for a pin 195 on which a feeler finger 196 is loosely mounted. The finger has a T-shaped end, in order to engage the toe ends of variously shaped soles, and normally hangs in the opening 37 through which the soles are delivered to the table. The feeler 120 finger is provided with a contact arm 197 125

which, when there are no soles in the machine, swings by gravity into engagement with a contact 198, thereby completing an electrical circuit. As clearly shown in Fig. 8, when the lowermost sole S is ejected from the magazine, the feeler finger will swing counter-clockwise to allow the sole to pass there-beneath. After the sole has dropped, the feeler finger will swing back and if there is another sole in the magazine it will be stopped in the position shown. If there is no sole present in the magazine to stop the finger in this position, it will swing further until the contact arm 197 engages the contact 198, as shown at the left in Fig. 14, and completes a circuit. The feeler on one magazine is connected by wires 199 with a magnet 200 and the feeler on the other magazine is connected by wires 201 with a magnet 202.

The magnets are arranged so that the first one to be energized performs the preliminary step in stopping the machine, and the second one to be energized renders the stopping means operative. The magnets are mounted on the upper end of a lever 203 pivotally mounted at 204 (see Fig. 1) on the lower part of the machine frame. The lower end of the lever 203 is identical with the stop-mechanism commonly used on sole-molding machines of this type. The lower end of the lever is provided with a roll which is held to the left in Fig. 1 by a light spring 205. When the treadle 206 is depressed to start the machine, the roll on the lever 203 snaps over the top of a lug 207 on the treadle, holding it down until the lever is swung again to remove the roll from engagement with the lug. The treadle is connected by a link 208 with an arm 209 (Fig. 2) rigidly mounted on a rock shaft 210. The rear end of the rock shaft 210 carries a yoke 211 which is constructed to slide a collar 212 on the main driving shaft 213. The collar is constructed to engage one end of a lever 214, the other end of which controls an expansion ring 215, whereby when the collar is moved in the proper direction, the ring will be expanded to operatively connect the shaft 213 with a driving pulley 216. A spring 217 tends to hold the rock-shaft 210 in inoperative position.

The magnets 200 and 202 perform certain functions when they are energized, whereby the lever 203 is moved and the machine stopped by the action of one or the other of the toggles the next time it is brought into straightened position after both magnets have been energized. The mechanism which enables one of the toggles to move the lever 203 is carried on the upper end of this lever and comprises a three-arm carrier 220 hanging freely from a pivot screw 221 on the upper end of the lever 203. The middle arm 222 of the carrier hangs between the two

magnets so that it may be acted upon by either one. The carrier is also provided with two laterally extending arms 223, each of which has pivotally mounted at the end of the arm a swinging space-block lever 224. The upper end of each of the levers 224 is provided with a space-block 225 and the lower end is adapted at certain times to be acted upon by the outside end of one or the other of the magnets. The upper end of the lever 203 is forked and provided with two bosses 226, the faces of which are in sliding contact with the space-blocks 225. When neither of the magnets is energized, the carrier and the space-block levers hang in the position shown in Fig. 15. When in this position, the space-blocks are at one side of the path of two abutment screws 227, one carried by each of the lower toggle links 167. When one of the toggles is straightened, at the time the sole is under pressure, the abutment screw 227 has passed by the space-block 225 and the screw is adjusted to such a position that it does not engage the boss 226 on the upper end of the lever 203. The positions of the two abutment screws 227 are indicated in broken lines in Fig. 15.

Assuming that the soles in the left-hand magazine have become exhausted, as indicated by the position of the feeler finger 196 in Fig. 14, the circuit through the wires 201 is then closed and the magnet 202 is energized. This causes the carrier 220 to swing to the right, thereby lowering the pivot of the left space-block lever 224 so that the space-block is substantially in line with the center of the co-operating boss 226. The parts are held in this position with both space-blocks at one side of the paths of travel of the abutment screws 227 until the soles in the other magazine have become exhausted. When the soles in the right-hand magazine have become exhausted, the feeler finger will close the circuit through the wires 199 and the magnet 200, which will then act on the space-block lever 224 and cause the space-block to swing into the path of movement of the abutment screw 227 on that side of the machine. When the toggle next approaches the straight position, the abutment screw will strike the space-block 225 and will swing the lever 203 towards the observer in Fig. 14, or to the left in Fig. 1, which will free the treadle 206 from the lower end of the lever and allow it to rise under the action of the spring 217 and stop the machine.

The space-block levers 224 are normally held in the position shown in Fig. 15 by light springs 228, which hold the levers against stop-pins 229 on the carrier 220. In order that the action of the first magnet energized may be exerted on the central arm 222 of the carrier and not upon the lower end of one of the space-block levers 224, the

space-block levers are locked in the position shown until after the carrier has been swung to one side or the other of the center. After the carrier has been so swung, the space-block lever, which has been depressed so as to bring it into operative relation with the magnet, is released from the control of the lock. The locking device comprises a lug 230, one on each of the arms of the lever 203, and a co-operating pin 231 in the space-block lever 224. As shown in Fig. 14, the left-hand space-block lever has been swung downwardly so that the pin 231 is free to swing below the lug 230 while the corresponding pin and lug on the other side are still in locking relation. By this construction the first magazine to become emptied swings the parts into such a position that when the second magazine has become emptied the stop-mechanism will be rendered operative by moving one of the space-blocks to such position that it will be struck by the abutment screw 227 the next time the toggle is straightened.

While the features described above are well adapted for use in a sole molding machine, it is to be understood that except as defined in the claims the several features of the present invention are not limited to use in a machine of this type.

The nature and scope of the present invention having been indicated and a machine embodying the several features of the invention in their preferred form having been specifically described, what is claimed is:

1. A machine for operating upon shoe soles having, in combination, sole molding instrumentalities, a sole magazine, mechanism for feeding the soles independently from the magazine to the molding instrumentalities, and means for locating the individual soles prior to feeding the soles into operative relation to the molding instrumentalities and after the soles leave the magazine.

2. A machine for operating upon shoe soles having, in combination, operating instrumentalities, a magazine, mechanism for feeding the soles individually from the magazine to the operating instrumentalities including two slides, and means for moving one of the slides a variable distance depending upon the length of the sole, and for moving the other slide a predetermined distance independently of the length of the sole.

3. A machine for operating upon shoe soles having, in combination, operating instrumentalities, a magazine, feeding mechanism located beneath the magazine, means for causing individual soles to drop from the magazine on to the feeding mechanism, and means for locating each sole so dropped upon the feeding mechanism prior to feed-

ing the soles into operative relation to the instrumentalities.

4. A sole molding machine having, in combination, a pair of co-operating molds, a feed slide for transferring soles to a position between the molds, a magazine located a distance above the feed slide, and means for causing individual soles to be deposited upon the feed slide from the magazine.

5. A sole molding machine having, in combination, a pair of co-operating molds, a magazine, means for transferring the soles successively from the magazine to an operative position between the molds, and for removing the soles from operative position between the molds at the completion of the molding operation, said means comprising a sole gripping device for holding the sole in position between the molds during the first part at least of the molding operation, and means for ejecting the soles thus removed from the transferring means.

6. A machine for operating upon shoe soles, comprising operating instrumentalities, a magazine, a finger constructed and arranged to deliver individual soles from the magazine, means for reciprocating the finger longitudinally beneath the magazine, means for causing the finger to engage and deliver a sole from the magazine upon movement in one direction only, and a slide for then delivering the sole to the operating instrumentalities.

7. A machine for operating upon soles, comprising operating instrumentalities, a magazine, an endless belt supported beneath the magazine, a pivoted sole delivering finger mounted upon the belt, means for reciprocating the finger longitudinally beneath the magazine, and feeding means adapted to receive individual soles thereon as they are dropped from the magazine by the finger and to feed them to the instrumentalities.

8. A machine for operating upon soles, comprising a table, a magazine mounted above the table, means for delivering individual soles from the magazine and thereafter causing them to drop upon the table, and a pair of gaging fingers adapted to contact with opposite sides of the sole to position the sole after it is dropped upon the table.

9. A machine for operating upon soles, comprising a table, a magazine spaced a distance above the table, means for delivering individual soles from the magazine to the table, and means comprising gages engaging opposite sides of the soles for positioning the soles thus delivered to the table both longitudinally and laterally.

10. A machine for operating upon soles having, in combination, a table, a magazine mounted above the table, means for deliver-

- ing individual soles from the magazine to the table, and a pair of gaging fingers adapted to contact with opposite sides of the shank of the sole to position the sole laterally after it is delivered to the table. 5
11. A machine for operating upon soles, comprising sole centering devices, means for automatically delivering individual soles to the centering devices, operating instrumentalities, and means for transferring a sole to the operating instrumentalities after its location by the centering devices. 10
12. A machine for operating upon soles, comprising a magazine, a transferring slide, means for delivering individual soles upon the transferring slide from the magazine, means for centering the soles thus delivered to the slide, a vertically movable sole mold, and means for causing the transferring slide 15 to partake of the vertical movement of the sole mold independently of the magazine. 20
13. A machine for operating upon soles, comprising a pair of sole positioning arms adapted to contact with opposite sides of a sole, a transferring slide, sole operating instrumentalities, means for actuating the transferring slide toward and from the instrumentalities, and means for first opening the arms and for thereafter permitting the closure of the arms on the sole during the movement of the transferring slide away 25 from the operating instrumentalities. 30
14. A machine for operating upon soles having, in combination, sole operating instrumentalities, a transferring slide, means for moving the transferring slide toward and from said instrumentalities, means for positioning a sole placed on the transferring slide comprising a pair of gages adapted to 35 contact with opposite sides of the sole, and means for first spreading the gages to permit a sole to be placed between them, and for thereafter closing the gages on the sole during the movement of the transferring 40 slide away from the operating instrumentalities. 45
15. A machine for operating upon soles, comprising operating instrumentalities, a transferring slide for transferring a sole to said instrumentalities, mechanism for actuating the slide, means for centering a sole upon the slide both laterally and longitudinally, and means on the slide for automatically gripping the sole after its location by 50 the centering devices. 55
16. A machine for operating upon soles, comprising upper and lower transferring slides, means for gaging the position of a sole upon the upper slide, connections between the two slides controlled by the gaging means, and mechanism for imparting a movement of uniform extent to the lower slide. 60
17. A machine for operating upon soles, comprising upper and lower transferring slides, means for imparting a movement of uniform extent to the lower slide, and connections between the upper and lower slides for imparting a movement of variable extent to the upper slide controlled by the length of the sole positioned upon the slide. 65
18. A machine for operating upon soles, comprising a transferring slide, means for centering a sole longitudinally upon the slide, and mechanism for actuating the slide controlled by the sole centering means. 70
19. A machine for operating upon soles, comprising a transferring slide, means for automatically delivering individual soles to the slide, means for centering the soles longitudinally upon the slide, and mechanism for actuating the slide controlled by the sole centering means. 80
20. A machine for operating upon soles, comprising a table upon which a sole is supported, means for centering the sole longitudinally upon the table, a gripping device, and mechanism controlled by the sole centering means for causing the gripping device to engage with the sole when properly centered upon the table. 85
21. A machine for operating upon soles, comprising a table, gages adapted to contact with opposite ends of a sole, mechanism for moving the gages toward one another at the same rate of speed to center the sole longitudinally, and means for automatically gripping the sole after it has been centered between the gages. 90
22. A machine for operating upon soles, comprising a transferring slide, a gage adapted to contact with one end of the sole movable with the slide, a gage for the opposite end of the sole, and mechanism controlled by the movements of the slide for moving this second gage in the opposite direction to said movement of the first gage to center the sole between the gages. 100
23. A machine for operating upon soles, comprising a transferring slide, a gripping device, toe and heel gages, means controlled by the movements of the slide for causing the toe and heel gages to move toward one another at the same rate of speed to center a sole, and mechanism controlled by the pressure of the toe and heel gages upon the sole to actuate the gripping device. 110
24. A machine for operating upon soles, comprising a transferring slide, a lower slide, a gripping device, means for normally holding the gripping device in an inoperative position, means controlled by the gripping device for causing the two slides to move in unison, means for centering a sole longitudinally upon the upper slide, and mechanism controlled by the centering means for permitting the gripping device to engage the sole and disconnect the two slides. 120
- 115
- 125

25. A machine for operating upon soles, comprising a transferring slide, an actuating slide, connections between the two slides for causing them to move initially in unison, 5 means for centering a sole longitudinally upon the transferring slide, mechanism for disconnecting the two slides controlled by the sole centering means, means for measuring the movement of the transferring slide 10 prior to the disconnection of the two slides, and mechanism for imparting a movement of uniform extent to the actuating slide.
26. A machine for operating upon soles, comprising upper and lower slides, means 15 for imparting a movement of uniform extent to the lower slide, means for first centering and next gripping a sole to the upper slide, and connections controlled by the centering means for determining the extent of 20 movement of the upper slide by the lower slide.
27. A machine for operating upon soles, comprising an upper transferring slide, a lower slide, a gripping lever mounted upon 25 the upper slide, connections between the gripping lever and the lower slide for moving the two slides in unison when the gripping lever is in an inoperative position, means for locking the gripping lever in inoperative position, means for normally moving the gripping lever into an operative position, a sole gage, and connections between the sole gage and locking means 30 for disengaging the locking means 35 when the sole gage contacts with the sole.
28. A machine for operating upon soles, comprising a transferring slide, a pair of side gages adapted to contact with the side edges of a sole to position the sole laterally, 40 a pair of end gages, means for moving the end gages together to center the sole longitudinally, and mechanism controlled by the end gages for actuating the transferring slide.
29. A machine for operating upon soles, comprising a transferring slide, a toe gage normally located below the slide, a heel gage, and mechanism actuated by the movement of the slide for first moving the toe 45 gage into an operative position above the slide and for thereafter moving the toe gage toward the heel gage.
30. A machine for operating upon soles, comprising a magazine, operating instrumentalities, a transferring slide for conveying 50 individual soles from the magazine to the operating instrumentalities, and mechanism controlled by the length of each sole to vary the extent of movement of the transferring slide toward the operating instrumentalities.
31. A machine for operating upon soles, comprising a magazine, operating instrumentalities, a transferring slide, means for 55 delivering individual soles from the magazine to the slide, means for centering the soles thus delivered upon the slide, and mechanism for actuating the slide controlled by the sole centering means.
32. A machine for operating upon soles, 70 comprising an upper slide, a lower slide, means for moving the two slides in unison, a measuring bar, means for normally holding the measuring bar stationary, means for disconnecting the two slides and simultaneously locking the measuring bar to the upper slide, and means for thereafter connecting the upper slide to the lower slide through the measuring bar.
33. A machine for operating upon soles, 75 comprising upper and lower slides, mechanism for centering a sole longitudinally upon the upper slide, a measuring bar, means for initially connecting the two slides to cause them to move in unison, means for holding the measuring bar stationary during the initial movement of the slides, means controlled by the centering devices for disconnecting the two slides and for locking the measuring bar to the upper slide and means 80 for thereafter actuating the upper slide from the lower slide through the measuring bar.
34. A sole molding machine, comprising upper and lower sole molds, means for moving the lower mold toward and from the 85 upper mold, a transferring slide for conveying individual soles to the lower mold, and connections for causing the transferring slide to move with the lower mold when the slide has reached the limit of its movement 90 toward the lower mold.
35. A sole molding machine, comprising upper and lower molds, mechanism for moving the lower mold toward and from the upper mold, means for independently adjusting the vertical position of the lower mold, a transferring slide for delivering individual soles to the lower mold, and connections between the mold and transferring slide for causing the latter to partake of 95 the vertical movements of the lower mold when the sole carried by the slide is positioned on the mold.
36. A sole molding machine, comprising upper and lower sole molds, mechanism for 100 relatively actuating the molds, a transferring slide for conveying individual soles to and from an operative position between the molds, and means for automatically locating and clamping the sole upon the transferring slide prior to its delivery between the molds.
37. A sole molding machine, comprising upper and lower sole molds, mechanism for actuating the lower mold including a toggle lever, a transferring slide for conveying 105 soles to and from the lower mold, and connections between the toggle lever and transferring slide for actuating the slide.
38. A sole molding machine, comprising upper and lower sole molds, mechanism in- 110

cluding a toggle lever for moving the lower mold toward and from the upper mold, a magazine, a transferring slide, means for delivering individual soles from the magazine upon the slide, and mechanism actuated by the toggle lever for moving the transferring slide and for actuating the sole delivering means.

39. A machine for operating upon soles, comprising operating instrumentalities, a transferring slide, means for gaging the position of a sole upon the slide, mechanism for moving the slide toward the operating instrumentalities and for withdrawing the slide after the operating instrumentalities have performed the designated operation upon the sole, and means for ejecting the sole from the slide during the return movement.

40. A machine for operating upon soles, comprising a transferring slide, a pair of side gaging fingers for locating a sole upon the slide, operating instrumentalities and mechanism for moving the slide toward and from the operating instrumentalities, an ejecting finger, and mechanism for actuating the ejecting finger to remove the sole from the slide upon the return movement of the slide.

41. A machine for operating upon soles, comprising a table, a pair of sole end gages, mechanism for moving the end gages toward one another to center the sole longitudinally upon the table, a pair of side gages adapted to engage with the opposite edges of the sole intermediate the ends, and means upon the side gages for holding the sole flat upon the table under the pressure of the end gages.

42. A machine for operating upon soles, comprising a transferring slide, a heel gage comprising a pair of separable wings, a toe gage, means for moving the two gages toward one another at the same rate of speed to center a sole longitudinally, and a detecting finger positioned between the wings of the heel gage and adapted to control the movements of the transferring slide when the heel end of the sole spreads the wings of the heel gage apart and contacts with the finger.

43. A sole molding machine, comprising two pairs of co-operating molds, mechanism for alternately moving the molds into and out of operative position, a magazine and a transferring slide for each pair of molds, mechanism for delivering soles individually from each magazine to the co-operating slide and for actuating the slide to transfer a sole between the molds, and mechanism for stopping the machine when the supply of soles in both magazines is exhausted.

44. A machine for operating upon soles, comprising operating instrumentalities, a sole magazine, a transferring slide, actuati-

ing mechanism for causing individual soles to be automatically delivered from the magazine to the operating instrumentalities, and means for stopping the actuating mechanism when the supply of soles within the magazine is exhausted.

45. A machine for operating upon soles, comprising a pair of co-operating sole molds, a magazine, a transferring slide, means for gaging the position of a sole upon the slide after it is delivered thereto by the magazine, means for causing the delivery of individual soles from the magazine to the slide, and means for automatically controlling the extent of movement of the slide in accordance with the length of the sole positioned thereon.

46. A machine for operating upon soles, comprising a duplicate set of operating instrumentalities, a magazine for each set of operating instrumentalities, mechanism for actuating the machine to cause individual soles to be successively delivered to and removed from the operating instrumentalities, and controlling mechanism for stopping the machine when the supply of soles in both magazines is exhausted.

47. A machine for operating upon soles having, in combination, a pair of cooperating sole molds, a sole magazine, mechanism for feeding the soles individually from the magazine to a position between the molds, and means for automatically locating the longitudinal center of the soles in a definite position relatively to the molds independently of variations in the lengths of the soles.

48. A machine for operating upon soles having, in combination, a magazine, a table, means for feeding the soles independently from the magazine to the table, and means for automatically locating the longitudinal center of the soles in a definite position on the table independently of variations in the lengths of the soles.

49. A machine for operating upon soles having, in combination, a sole magazine, operating instrumentalities, a transferring slide for conveying individual soles from the magazine to the operating instrumentalities, actuating mechanism for the slide, and means for controlling said actuating mechanism to vary the extent of the movements of the slide toward the operating instrumentalities in accordance with variations in the lengths of the soles.

50. A machine for operating upon soles having, in combination, a sole magazine, operating instrumentalities, means for feeding the soles from the magazine to the operating instrumentalities a distance dependent upon the length of the sole and then a fixed distance to said operating instrumentalities.

51. A machine for operating upon soles having, in combination, a sole magazine,

cooperating upper and lower molds, means for transferring the soles from the magazine to the molds, mechanism comprising a toggle for moving the lower mold toward and from the upper mold, mechanism actuated by the toggle for stopping the machine, and means for controlling said mechanism to stop the machine when the soles in the magazine are exhausted.

5 52. In a machine of the class described, a means for operating upon a shoe sole, a magazine arranged to hold a supply of soles, a means for supporting the sole outside the magazine, means for transferring the soles one by one from the magazine, and feeler mechanism in connection with the supporting means constructed and arranged to cooperate with a characteristic contour of a sole on the supporting means to adjust 10 the sole completely in reference to the operating means prior to the contact of the operating means with the sole.

53. In a machine of the class described, a means for operating upon a shoe sole, a magazine arranged to hold a supply of soles, a means for supporting the sole outside the magazine, means for transferring the soles one by one from the magazine, and feeler mechanism in connection with 15 the supporting means constructed and arranged to cooperate with a characteristic contour of a sole on the supporting means to adjust the sole completely longitudinally and laterally in reference to the operating means prior to the contact of the operating means with the sole.

54. In a machine of the class described, a means for operating upon a shoe sole, a magazine arranged to hold a supply of soles, a means for supporting the sole out-

side the magazine, means for transferring the soles one by one from the magazine, and feeler mechanism in connection with the supporting means constructed and arranged to cooperate with a characteristic 45 contour of a sole on the supporting means to adjust the sole completely laterally of itself in reference to the operating means prior to the contact of the operating means with the sole.

55. In a machine of the class described, a means for operating upon a shoe sole, a magazine arranged to hold a supply of soles, a means for supporting the sole outside the magazine, means for transferring the soles 50 one by one from the magazine, and feeler mechanism in connection with the supporting means constructed and arranged to cooperate with a characteristic contour of a sole on the supporting means to orient the sole completely in reference to the operating means prior to the contact of the operating means with the sole.

56. In a machine of the class described, a means for operating upon a shoe sole, a magazine arranged to hold a supply of soles, a means for supporting the sole outside the magazine, means for transferring the soles one by one from the magazine, and feeler mechanism in connection with 55 the supporting means constructed and arranged to cooperate with a characteristic contour of a sole on the supporting means to adjust the sole completely in reference to the operating means prior to the contact 70 of the operating means with the sole irrespective of variations in the size or shape of the sole.

LEWIS J. BAZZONI.
